[57] CLAIM

The ornamental design for a birdfeeder, as shown and described.

DESCRIPTION

FIG. 1 is a perspective view of a birdfeeder showing our new design;

FIG. 2 is a side elevational view thereof, the other sides being the same as the side shown;

FIG. 3 is a top view thereof; and,

FIG. 4 is a bottom view thereof.

It is to be understood that the roof pattern is continuous throughout the area indicated in FIGS. 2 and 3.
